TIRE

Seyed Khalil, New York, N. Y.

Application September 17, 1947, Serial No. 774,516

16 Claims. (Cl. 152—340)

1

This invention relates to improvements in pneumatic tires, and is more particularly directed to a pneumatic casing which is provided with two separate chambers concentric with each other and separated by an annular member which not only separates the two chambers, but which also braces the side walls of the casing for reducing the lateral flexure of the side walls.

This application is a continuation in part of my copending applications Serial No. 740,530, filed April 10, 1947, and Serial No. 762,271, filed July 21, 1947.

In the first mentioned copending application, an ordinary casing is divided into two chambers by means of a shield or partition and these chambers are called "primary" and "secondary" chambers, respectively. The primary chamber lies between the rim and the shield and the secondary chamber, between the shield and the inner surface of the tread of the casing. A pneumatic tube is positioned in the primary chamber and is called a "primary" tube and another tube is mounted in the secondary chamber and is called a "secondary" tube.

The second mentioned copending application describes and shows the individual valves for each of the primary and the secondary tubes and the inflation of these tubes independently of each other.

In these applications, it is described that when the secondary tube is punctured, the primary tube will support the load on the wheel, particularly if the speed of the vehicle is reduced. Thus, it can be seen that in both said copending applications, I have devised two tubes having individual inflating valves and a shielding means between said tubes, to be used in a casing of the prior art.

The flexure of such casings occurs partly in the primary chamber and partly in the secondary chamber due to the fact that the average casing flexes through an arc extending from the tread of the casing to the rim of the wheel when supports the casing. Therefore, the sides of the casing which normally contact the edges of the shield move away from said edges in the part of the casing where the flexure occurs. In order to prevent either one of the tubes being caught between the sides of the casing and the edges of the shield, it was necessary to apply a fabric to the shield to prevent the tubes from being injured by the shield.

One of the objects of the present invention is the provision of a casing with annular webs extending toward each other within the casing from

5 the sides thereof, and a shield interlocking with said webs and thereby functioning as (1) a shield to divide the interior of the casing into two chambers, and (2) as a bracing means for minimizing and/or nullifying the flexure of the side walls of the tire outwardly.

Another object of the invention is the provision in a casing of means within the casing interlocking with the side walls thereof and dividing the casing into two isolated chambers, a separate tube in each chamber, said tubes being individually inflatable, the tube in one of said chambers being inflated to a pressure permitting that section of the casing to be flexed to a minimum, thereby imparting to it load-supporting qualities, and the tube in the other chamber being inflated to a lower pressure to localize the major portion of a flexure therein for easy riding qualities.

20 Another object of the invention is the provision in an arrangement such as described above, of a tube in one of the chambers for effecting a fluid-tight seal with said dividing means, thereby making the other chamber fluid-tight, and the further provision of means for inflating said fluid-tight chamber.

25 Another object of the invention is the provision in a casing of means within the casing interlocking with the side walls thereof and dividing the casing into two isolated chambers, a separate tube in each chamber, said tubes being individually inflatable, the tube in the chamber next to the wheel supporting the tire being inflated to a pressure permitting that section of the casing to be flexed a minimum, thereby giving it load supporting qualities, and the tube in the chamber adjacent to the tread being inflated at a lower pressure, whereby the major portion of the flexure is localized in said last mentioned chamber for easy riding qualities.

30 Yet another object of the invention is the provision in a casing of means to damp the flexing of the side walls thereof, which includes annular webs formed integral with said side walls and extending toward each other within the interior of the casing, each of said webs carrying engageable grooves and a laminated interlocking shield member within said casing, at least one of said laminae having extensions adapted to engage said locking grooves and form with said webs, bracing means extending through said tire from side wall to side wall, thereby dividing the interior into two isolated chambers.

35 A further object of the invention is the provision in a casing of means to damp the flexing

of the side walls thereof, which includes annular webs formed integral with said side walls and extending toward each other within the interior of the casing, each of said webs carrying engageable grooves and a laminated interlocking shield member within said casing, each of said laminae carrying hook means adapted to engage said grooves and form with said webs, bracing means extending through said tire from side wall to side wall, thereby dividing the interior into two isolated chambers.

A further object of the invention is to provide in a casing intermediate the distance between the tread and the rim upon which the casing is mounted, a nodal annulus in which flexure is discouraged, leaving the greatest amplitude of flexure in a zone intermediate said nodal annulus and said tread, and in a second zone intermediate said nodal annulus and the rim upon which said tire is mounted. This is not only important in normal use of the tire but is also particularly important when the vehicle upon which the tire is mounted is going around curves, because in the latter instance, the flexure in tires of the prior art is a maximum in the zone corresponding to the zone in which I have the nodal annulus, and consequently have a minimum of flexure.

Other objects and advantages of the invention will be apparent to those skilled in the art from a study of the following specification and the accompanying drawings, in which:

Figure 1 is a side elevation of my new and improved tire mounted on a rim, certain portions having been cut away to show the interior;

Figure 2 is a sectional elevation of my new and improved tire, taken along the line 2—2 of Figure 1;

Figure 3 is a sectional view taken along the line 3—3 of Figure 2;

Figure 4 is an elevation, partly broken away, showing my new and improved laminated shield and bracing member, one face being partly broken away to show the tabs or hooks formed on the outer one of the two ring laminations;

Figure 5 is a sectional view of the interlocking laminated rings, forming the shield and brace of Figure 4 and showing the interlocking of the two laminated ring members by means of dowels and dowel holes;

Figure 6 is a fragmentary view of a portion of one of the laminated rings showing the tabs or hook members before they are bent at right angles to the ring per se;

Figure 7 is a view similar to Figure 6, except that the hooks or tabs have been bent at right angles to the web of the ring, itself;

Figure 8 is a sectional elevation similar to Figure 2, except that it represents a modification of the arrangement shown in Figure 2, wherein the interior of the casing is divided into two chambers, one of which is adapted to contain a pneumatic tube and the other of which is adapted to form an air chamber without a tube therein and which also may include a self-healing compound adapted to heal punctures formed in the casing adjacent to the tread of said last mentioned chamber;

Figure 9 is a sectional view taken along the lines 9—9 of Figure 2, and showing the non-collapse tube which extends from one of the valve stems to either the tube in the outer chamber as shown in Figure 2, or to the tubeless chamber, shown in Figure 8; and

Figure 10 is an enlarged sectional view showing

one method of delivering air to the tubeless chamber in the modification shown in Figure 8.

Referring first to Figure 1, a wheel rim 20 has my new and improved casing, generally designated by the numeral 22, mounted thereon. The rim 20 may have a hole formed therein to accommodate a valve stem 23 which is used to inflate the tube 24, and a second hole to accommodate a valve stem 25, which is used to inflate the tube 26. Within the casing, between the tubes 24 and 26, is a combination bracing member and shield, generally designated by the numeral 21.

Referring to Figures 1, 2 and 3, the casing 22 has a tread 27 secured to the curved portion 28 of the casing structure. The inner surface 29 of the structure 28 is curved laterally from the point 30 to the point 31 and forms the outer boundary of the chamber which is occupied by the tube 24. This chamber, according to the afore-mentioned copending applications, is termed a "secondary chamber." Forming a continuation of the surface 28 from the point 30, is a curved surface 29a of a substantially shorter radius than the curve of the surface 29.

Extending inwardly from the wall of the structure 28 below the curved portions 28 and 29a is an annular web 32 which extends within the casing toward the opposite wall thereof. The upper surface of this web, as may be seen in Figure 2, is curved with what is the equivalent of a large chamfer and beneath the chamfer and extending into the web 32 from its lower surface is an annular groove 33. The right edge of the annular groove 33 terminates in the normal under-surface 32a of the web 32 and the left edge of the groove 33 has a stepped portion 32b against which my new and improved shielding and bracing means, which will presently be described, rests, with the result that the under-surface of the shielding and bracing means is substantially flush with the surface 32a. Where the lower surface 32a of the annular web 32 joins the inner surface 38 of the side wall portion 28a (which forms a wall of the primary chamber) a smooth hollow curve 38a is provided. This curve would correspond to a fillet which lends rigidity and strength to the annular web 32 and insures that if there is any flexing in the chamber occupied by the tube 26, the amplitude of such flexing will occur in the side wall 28a between the curved portion 32a and the bead edge 34 which engages the rim upon which the casing is mounted.

Within the casing and extending laterally toward and in alignment with the annular web 32 is a second annular web 35. This annular web is not seen in Figure 2, in view of the fact that it is notched, as shown in Figure 3, to accommodate a filler member which is formed integral with the inflating valve, still to be presently described. However, a fragmentary portion of the web 35 is shown in Figure 3, and an annular groove 36 is formed therein and is preferably identical with the annular groove 33.

Within the chamber which accommodates the tube 24, the inner surface 29b is curved, and due to the fact that the annular web 35 is formed integral with the wall of the casing, flexure of the casing is discouraged in the area adjacent to the annular web 35. In fact, the annular webs 32 and 35, when interlocked with the bracing means to be presently described, may be said to constitute nodal rings in which flexure is discouraged and consequently reduced to a minimum. The side wall 28b terminates in a bead ring 37. The space between the annular webs 32 and 35 is provided

so that the tube 24 may be easily placed in the secondary chamber 61. A clearance slot 39 is formed in the annular web 35 to accommodate the stem 40 of the inflating valve 23 which is provided for inflating the tube 24. This stem may be secured to a reinforcing plate 41 with an air hole 42 therein matching the air passage 43 in the stem 40 and also matching the air hole 44, so that air may pass from the passage 43 into the tube 24.

Secured to the stem 40 and to the surface of the tube 24 is a filler member 45 which may be made of any desirable material. However, I prefer to form this of rubber. The filler member has formed therein a slot 46 which, when the tube 24 and the stem 40 are positioned in the casing, coincides with the groove 36 formed in the web 45 as the filler member fills up the slot 39. When the tube 24 and the stem 40 are installed as described, the valve stem 23 extends through the opening in the casing, ready to be inserted in the hole provided for it in the rim 20, as the casing is being mounted on the rim 20.

The next step is to position my new and improved shield and bracing member in the casing.

Referring now to Figures 4 and 5, the shield and bracing member is formed of a spring ring 47 interlocked with a second spring ring 48. The spring ring 47 carries a dowel pin 49 adjacent to the end 47a thereof, and a second dowel pin 50 adjacent to the end 47b thereof. The dowel pin 49 fits in a hole 51 and the dowel pin 50 fits in a hole 52. Spaced apart approximately 120° from the point of adjacency of the ends of the ring 47 are the ends 48a and 48b of the ring 48. Adjacent to the end 48a of the ring 48 is a dowel hole 53 which accommodates a dowel pin 54 carried by the ring 47, and adjacent to the end 48b of the ring 48 is a hole 55 which accommodates a dowel pin 56 carried by the ring 47. The ring 47 has disposed about its circumference along each edge thereof, a plurality of projecting tabs 57, and the ring 48 has disposed about each edge of its circumference a plurality of tabs 58. These tabs extend radially and consequently lie in planes cutting the axis of the shielding and bracing member in four planes spaced apart from each other.

In forming the shielding and bracing rings, the form of blank is shown in Figure 6, and Figure 7 shows the ring after it has been formed by bending the tabs. In Figure 6, the web of the ring is designated by the numeral 47 and the tabs are designated by the numerals 57. In Figure 6, the tabs 57 lie flat just as they are blanked from the dies, and in Figure 7, the tabs 57 are shown as bent to form right angles with the web 47. In forming the web 48, the blank is like the blank shown in Figure 6, except that the web is slightly narrower and the tabs are also slightly narrower.

In positioning the shield and bracing member in the casing, Figure 2, the ring 48 is first spiraled up so that it will be small enough to be inserted in the opening in the casing. After it is inserted and released, it tends, due to the fact that it is preferably made of spring material, to expand to its full diameter, and it is only necessary to make sure that the tabs 58 engage the sides of the grooves 33 and 36 and that the ends of the ring abut each other. Then, the ring 47 is spiraled up in the same manner so that it may be inserted in the casing, and as it is released, it is necessary for the operator to insure registration of the dowel pins with the dowel holes. If the operator makes sure that the dowel pin 50, for example, engages the dowel hole 52, he is off to a good start. Then, he makes sure that the dowel pins 54 and

56 engage the holes 53 and 55, respectively, and then he will find it very easy to engage the dowel pin 49 with the dowel hole 51, and thus the two spring rings are in position in the casing.

5 The operator may then insert the tube 26 in the casing with its valve stem 25 in the proper position. I have found that it is expedient to provide a marker on the casing bead 37 to guide the operator in positioning the valve stem 23, and the provision of a second marker on the bead 37 indicates the position of the valve stem 25.

10 After the tube 26 has been properly inserted in the casing, the whole array is ready to be mounted on the rim 20. The first step is to position the valve stems 23 and 25 in corresponding holes in the rim and then to work the casing onto the rim in each direction around the circle from the valves so that the last portion of the tire placed on the rim is diametrically opposite the valve stems 23 and 25. Obviously, a little air may be inserted into both tubes to facilitate the mounting of the array on the rim.

15 Since the tubes are individually inflatable, they may be inflated in accordance with the type of service desired. For example, if it is desired to have the flexure localized in the outer chamber (the chamber between the tread and the shielding and bracing means), the tube 24 may be inflated to a lower pressure than that of the tube 26, in which event, most of the flexure of the casing will be localized in said chamber. For other types of service, the pressure arrangements in the two tubes may be varied in accordance with the results desired. When the tube 26 is inflated (Figure 9) a portion 26a of its wall embraces or spans the stem 40, thereby holding it firmly against the inner surface of the casing wall 28b. By providing the stem 40 with fabric or other reinforcing means 40a, the stem is prevented from collapsing under the urge of the pressure in the tube 26.

20 In the modification shown in Figures 8 and 10, those parts which are identical with those shown in Figure 2 are given the same numerals and the new elements are given different numerals. In this modification, the outer chamber is rendered fluid-tight by the tube in the chamber between the shielding and bracing means and the rim so that it may be inflated without the necessity of having to have a tube therein.

25 Referring to Figures 8 and 10, the casing 22 is mounted on a rim 20 which may have a hole formed therein to accommodate a valve stem 60 which is used to inflate the chamber 61. A second hole in the rim accommodates valve stem 25 which is used to inflate tube 26. Within the casing, dividing the interior thereof into the chamber 61 and the chamber 62 which contains the tube 26, is my new and improved combination bracing member and shield, generally designated by the numeral 21, and which is comprised of an annular spring rings 47 and 48.

30 The casing 22 has a tread 27 secured to the curved portion 28 of the casing structure. The inner surface 29 of the structure 28 is curved laterally from the point 30 to the point 31 and may be coated with a layer 63 of material adapted to enter into and stop leaks through holes formed in the casing in or adjacent to the tread 27. This surface 29, together with the layer 63, forms the outer boundary of the chamber 61. Forming a continuation of the surface 29 from the point 30, is a curved surface 29a of substantially shorter radius than that of the surface 29.

35 Extending inwardly from the wall of the structure 28 below the curved portions 29 and 29a is

7

an annular web 32 which extends within the casing toward the opposite wall thereof. The upper surface of this web is curved to form a large chamfer and beneath the chamfer and extending into the web 32 from its lower surface is an annular groove 33. The right edge of the annular groove 33 terminates in the normal under-surface 32a of the web 32 and the left edge of the groove 33 has a stepped portion 32b against which my new and improved shielding and bracing means rests, with the result that the under-surface of the shielding and bracing means is substantially flush with the surface 32a.

Where the lower surface 32a of the annular surface 32 joins the inner surface 38 of the side wall portion 28a, which forms a wall of the primary chamber, a smooth hollow curve 62a is provided. This curve forms a fillet which lends rigidity and strength to the annular web 32 and insures that any flexing which occurs in the side wall of the casing is localized either in one or in both of said chambers according to the ratio of the pressures therebetween. In other words, the annular web 32 forms a nodal annulus in which flexing is discouraged.

The portion of the side wall 28a terminates in a bead edge 34 and is adapted to engage the rim upon which the casing is mounted. Within the casing and extending laterally toward and in alignment with the annular web 32 is a second annular web 35. This annular web has between it and the curved surface 38 a curved portion 28b. This annular web is similar to the web 32, with the exception that a metallic insert 64 is molded into it. This insert, which may be seen in detail in Figure 10, has a central hole 65 therethrough and is provided with a series of steps 66 which serve to retain it in the juncture of the web 35 with the side wall 28b.

The hole 65, at least in its radially inner end, is provided with threads 67 adapted to be engaged by corresponding threads on a nipple 68, which is secured in the end of a stem 69, which is employed to inflate the chamber 61. The valve stem 69 is secured to the lower end of the stem 68. The stem is constructed very much in the same manner as the stem 48 above described, and it includes reinforcement 69a which may be fabric, or any other suitable material.

The web 35 has an annular groove 36 formed therein and the under-surface of the web is stepped exactly in the same manner as described in connection with the under-surfaces 32a and 32b of the web 32.

In assembling the tire of the modified form, such as that shown in Figure 8, the bracing and shielding members 43 and 47, respectively, are inserted into the casing in the same manner as described in connection with Figure 2, with the exception that the tube in the secondary chamber 61 is omitted. The stem 69 is mounted in the casing by threadedly engaging the threads on the nipple 68 with the internal threads 67 formed in the insert 64 and screwing the nipple in until a seal is effected, making sure that the valve stem 69 is in a position to extend through the hole provided in the rim for that purpose. After the shield and bracing members 43 and 47 have been mounted in the casing and interlocked by engaging the dowels with the dowel holes, the tube 26 is placed in the chamber 62 with its valve stem the proper distance away from the valve stem 69 and then the casing is mounted on the rim.

In mounting the casing, the first step is to posi-

8

tion the casing so that the valve stems 68 and 25 register with corresponding holes in the rim and then the casing is gradually placed onto the rim in the manner described above in connection with Figure 2.

When the tube 26 is inflated, the portion 26a thereof is forced into sealing engagement with the lower surface of the ring 47 and is also forced into sealing contact with the lower surfaces of 10 the webs 32 and 35, thereby isolating the chamber 61 from the chamber 62 and making the chamber 61 fluid-tight, so that when air is 15 pumped into the chamber 61 via 68 and 69, the chamber 61 will receive and retain air at the desired pressure forced into the chamber 61 via the valve stem 69.

In the present instance, the pressure in the chamber 61 and the pressure in the tube 26 in the chamber 62 may be regulated in accordance 20 with the result desired. In other words, if it is desired to have the maximum flexure of the casing localized to the chamber 61, the pressure in the chamber 61 may be made lower than that of the pressure in the tube 26.

25 In the areas outside of the webs 32 and 35, the flexure is, due to the structure of the casing, and due to the presence of the interlocking bracing member, an irreducible minimum.

From the above, it will be seen that I have 30 provided in this invention a new and improved casing in which the flexure is controlled and localized into a desired portion or portions of the casing in accordance with the result desired.

If flexure occurs in the secondary chamber, 35 before the primary chamber undergoes any flexure, the time lag between the flexure of the secondary chamber and the time flexure takes place in the primary chamber, depends upon the degrees of air pressure in the chambers. It can 40 be seen that at certain stages, the cushioning of my casing is due to both secondary and primary flexure. This, I provide what might be termed a "compound cushion."

Although I have shown a preferred embodiment 45 of the invention and a modification thereof, it is obvious that many changes may be made in the arrangements herein shown and described within the scope of the appended claims.

What is claimed is:

50 1. In a tire, a casing having engageable annular extensions formed integral with the side walls thereof intermediate the tread and the bead of said casing, and removable means within the casing interlocking with said annular extensions to form nodal annulae therein, thereby defining on either side thereof localized zones in which maximum amplitudes of flexure may occur in said side walls.

55 2. A casing having a tread and side walls, means for damping flexure midway said side walls comprised of aligned annular webs extending laterally toward each other from said side walls within said casing, and bracing and shielding means removably mounted in said casing in interlocking relation with said webs.

60 3. A casing having a tread and side walls, means for damping said side walls against flexure substantially midway between said tread and the rim upon which said casing is mounted, comprised of annular non-metallic extensions of said side walls extending laterally toward each other within said casing intermediate the tread and the bead of said casing, and metallic bracing and 65 shielding means removably mounted in said 70 75 shielding means removably mounted in said

casing in interlocking relation with said extensions.

4. In a tire, a casing having a tread and side walls, aligned annular webs formed integral with said walls intermediate the tread and the bead of said casing and extending toward each other within said casing, bracing and shielding means removably mounted in said casing in interlocking relation with said webs and dividing the interior of said casing into two concentric annular chambers, and at least one inflatable tube positioned within one of said chambers.

5. In a tire, a casing having a tread and side walls, annular webs formed integral with said side walls and extending laterally toward each other within said casing, said webs being spaced apart from said tread, annular grooves formed in said extensions, and bracing and shielding means separably mounted in said casing and carrying extensions adapted to engage said grooves.

6. The invention according to claim 5, in which said bracing and shielding means is comprised of two interlocking spring rings which are doweled together as they are assembled into said casing and each of which carries a series of tabs engaging one of the grooves and a series of tabs engaging the other of said grooves.

7. In a pneumatic tire, a casing the interior of which is divided into two concentric annular chambers by annular means extending laterally within the casing and interlocked with the side walls thereof intermediate the tread and the bead of said casing.

8. In a tire, a casing having two concentric annular pneumatic chambers divided by an annular wall detachably interlocked with the side walls thereof intermediate the tread and the bead of said casing, and an inflated tube in at least one of said chambers.

9. In a tire, a casing having two concentric annular pneumatic chambers divided by an annular wall detachably interlocked with the side walls thereof intermediate the tread and the bead of said casing, said annular wall lying in a substantially narrow zone concentric with said tread and said bead, at least one of said chambers being adapted to contain a fully inflated tube when said casing is mounted on a supporting rim.

10. In a tire, a casing having two concentric annular pneumatic chambers, and means to reinforce the side walls of said casing, said means being formed in part of non-metallic extensions of the side walls of said casing intermediate the tread and the beads of said casing and extending towards each other, and formed in part of insertable means interlocking with said extensions to form a common boundary of the two chambers.

11. In a tire, a compound casing having two concentric annular pneumatic chambers formed therein, the inner surface of the outer chamber and the outer surface of the inner chamber being defined by a comparatively non-elastic annular wall secured to the side walls approximately midway between the tread and the beads of said casing and common to both chambers, said an-

nular wall being substantially parallel to the axis of said tire and being adapted to be removed to gain access to said outer chamber.

12. In a tire, a casing having two concentric annular pneumatic chambers each of which is subject to flexure, and an annular wall interlocked with and detachably secured to the side walls of said casing and common to both said chambers to prevent a zone at the intersection of said chambers from expanding as said chambers are flexed.

13. In a tire, a casing having two concentric annular pneumatic chambers, an inflatable air tube in at least one of said chambers, and an annular partition detachably interlocked with the side walls of said casing and common to both said chambers to prevent a zone at the intersection of said chambers from expanding due to the inflation of said tube.

14. In a pneumatic tire, a casing, an annular base member therein having its opposite edges detachably interlocked with the side walls of said casing approximately midway between the tread and the bead of said casing for dividing said casing into two concentric annular chambers, said annular member functioning both to form a dividing wall between and also to immobilize said side walls against flexure in a neutral zone between said chambers, while each of the chambers themselves are free to flex in localized central zones.

15. A casing having a tread and side walls, means for damping flexure midway said side walls, comprised of annular means detachably interlocked with and extending laterally from one to the other of said side walls across said casing intermediate the tread and the bead thereof.

16. In a pneumatic tire, a casing having a bead and a tread, an annular wall positioned within and detachably secured to the side walls of said casing and lying in a lateral zone intermediate and spaced apart from both said tread and said bead, thereby dividing said casing into two spaced concentric sections, said wall forming a substantially non-expansile brace for discouraging variations of the thickness of said casing axially when the same is subjected to a load.
